DESIGN FOR A DRESS

Bella C. Goldish, New York, N. Y.

Application January 15, 1940, Serial No. 89,460

Term of patent 3½ years

To all whom it may concern:

Be it known that I, Bella C. Goldish, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my design; and

Fig. 2 is the rear view thereof.

The characteristic feature of my design resides in the combination on the dress disclosed of the specific, covered button trim arranged about the neckline, on the sleeves, and over the surface of the skirt and blouse as shown.

I claim:

The ornamental design for a dress, substantially as shown and described.

BELLA C. GOLDISH.
